MANUEL NAVARRO AND EVERARDO NAVARRO, OF CELAYA, MEXICO.

HAND-FIREARM.

1,113,239.

Specification of Letters Patent.

Patented Oct. 13, 1914.

Application filed February 20, 1914. Serial No. 819,957.

To all whom it may concern:

Be it known that we, MANUEL NAVARRO and EVERARDO NAVARRO, both citizens of Mexico, and residents of Celaya, in the 5 State of Guanajuato, Mexico, have invented new and useful Improvements in Hand-Firearms, of which the following is a full, clear, and exact description.

The invention relates to hand firearms of 10 the Luger type, in which use is made of the recoil to render the firearm automatic as to ejecting shells and reloading.

The object of the invention is to provide 15 certain new and useful improvements in hand firearms of the type referred to whereby the firing may be produced periodically on the user pressing the trigger or the firing may be rendered continuous until all or 20 a desired number of cartridges have been fired.

In order to accomplish the desired result use is made of means connected with the locking and releasing lever for locking and releasing the firing pin, and controlled by 25 one of the rollers at the toggle joint of the toggle levers connected with the breech block.

A practical embodiment of the invention 30 is represented in the accompanying drawings forming a part of this specification, in which similar characters of reference indicate corresponding parts in all the views.

Figure 1 is a side elevation, partly in section, of an arm of the Luger type and provided with the improvement; Fig. 2 is a plan view of the same, parts being in section; Fig. 3 is an enlarged face view of the attachment on the locking and releasing lever for the firing pin; Fig. 4 is a plan view 40 of the same; and Fig. 5 is a perspective view of the connection between the trigger and the locking and releasing lever of the firing pin.

In the arm of the Luger type shown in 45 Figs. 1 and 2, the breech block A is mounted to slide lengthwise in suitable guideways arranged in the framework B and the said breech block is pivotally connected with the knee or toggle levers C, C' provided at the 50 joint C² with rollers D, D' adapted to travel up and down on the cam faces E of the butt piece E' forming part of the framework B. The roller D is adapted to engage a cam face F' on the rear free end of a spring 55 plate F adjustably secured on the outer side of the locking and releasing lever G

controlled by the trigger H (see Fig. 5), and adapted to engage a lug I projecting transversely from the firing pin (not shown).

The spring plate F is provided with longitudinally extending slots F², F³, of which the slot F² is engaged by a clamping screw J screwing in the locking and releasing lever G, and the slot F³ is engaged by a stud K 60 held on the said lever G. On loosening the clamping screw J the spring plate F may be moved forwardly into the inactive position shown in Figs. 1, 2, 3 and 4, and when this position is reached the screw J is 65 screwed up to fasten the spring plate F in position on the lever G. When the plate F is in this position its cam face F' is out of the path of the roller D and consequently the pistol can only be fired on pressing the 70 trigger H to cause the lever O to release the lug I of the firing pin.

It is understood that the locking and releasing lever G is provided with the usual 75 notch G' engaging the fulcrum L for the 80 lever G to swing on, and the said lever is also provided with the usual shoulder G² adapted to engage the lug I to hold the firing pin in locked position. The locking and releasing lever is normally held against outward movement by the free end N' of the 85 spring-pressed locking lever N fulcrumed at N² in the handle O and having a hand plate N³ normally projecting on the back of the handle O. The magazine P for the cartridges is removably held in the handle O 90 in the usual manner.

It is also understood that in firearms of the Luger type the breech block is moved rearwardly by the recoil and during this 95 movement the shell is extracted and the main spring is placed under tension so that after the force of the recoil is spent the main spring returns the breech block to closed position, but during the time the breech block 100 is in open position a cartridge is fed by the magazine into position for the breech block to push this cartridge into the barrel.

When it is desired to successively fire the pistol, the operator loosens the screw J and 105 then slides the spring plate F rearwardly into the position shown in dotted lines in Fig. 4. The spring plate F is secured in this adjusted position by screwing up the screw J. When the spring plate F is in this 110 rearmost active position it extends into the path of the roller D and consequently when

the breech block A is moved into closing position the roller D engages the cam face F' and bends the free end of the spring plate F outward thus placing the spring plate F under tension, as the lever G is held against outward movement by the end N' of the lever N.

When it is desired to fire the pistol automatically the operator presses the finger plate N³ forward so that the end N' swings downward and forward and out of engagement with the locking and releasing lever G, and when this takes place the spring arm F on account of being under tension swings the lever G outward whereby the lug I and consequently the firing pin is released and the pistol is fired the same as if the trigger H had been pressed. The firing is automatically repeated as long as the user keeps the hand plate N³ pressed. After the first shot is fired the breech block is moved rearwardly by the recoil and the roller D disengages the free end of the spring arm F to allow the lever G to be reengaged by the lug I of the firing pin, but when the toggle levers return and the breech block moves forward into closed position, the roller D again engages the free end of the spring arm F thus swinging the lever G outward to release the firing pin for firing the second shot. The above described operation is repeated after firing a shot and as long as the hand-piece N³ is kept pressed, but the firing can be stopped on the user releasing the hand-piece N³ to allow the free end N' of the lever N to reengage the lever G and prevent its outward movement by the action of the spring arm F. It is further understood that when the toggle levers C, C' straighten out, the barrel and the breech block again act as one piece while the lug I of the firing pin engages the shoulder G² to hold the percussion spring of the firing pin in pressed position until the lug I is released on imparting a swinging motion to the released lever G either by pressing the trigger H or

by the roller D acting on the spring plate F, as above explained. The spring arm F and the means for slidably attaching it to the lever G are the only new parts added to the 50 pistol of the type referred to.

Having thus described our invention, we claim as new and desire to secure by Letters Patent:

1. In a firearm of the type described, the 55 combination of a locking and releasing lever for locking and releasing the firing pin, a breech having a toggle joint provided with a roller, and means connected with the said locking and releasing lever and controlled 60 by the said roller for automatically unlocking the firing pin from the breech.

2. A firearm of the type described provided with a member adjustably secured on the locking and releasing lever for the firing 65 pin, the said member in one position being out of the path of one of the rollers of the breech and the said member in another position being in the path of the said roller to cause the latter to impart movement to the 70 said member and the said locking lever to automatically unlock the firing pin.

3. A firearm of the type described provided with a plate, and means for adjustably securing the said plate to the locking and 75 releasing lever of the firing pin, the said plate projecting rearwardly beyond the rear end of the said locking and releasing lever, and the rear end of the said plate having a cam face adapted to be engaged by one of 80 the rollers of the breech to automatically actuate the said locking and releasing lever to release the firing pin.

In testimony whereof we have signed our names to this specification in the presence of 85 two subscribing witnesses.

MANUEL NAVARRO.
EVERARDO NAVARRO.
